REFRACTORY BRICK CONSTRUCTION

Jay B. Tracy, Upper Darby, Pa., assignor to General Refractories Company, Philadelphia, Pa., a corporation of Pennsylvania

Application May 28, 1934, Serial No. 727,849

3 Claims. (Cl. 110—86)

My invention relates to refractory furnace linings and locomotive fire box construction and particularly to a novel brick adapted to be utilized in building circular furnace linings and fire box bridge walls in certain types of kilns, furnaces, stacks and locomotives.

In some form of kilns, furnaces, stacks and locomotives sections are of cylindrical cross section and in order to build a lining or bridge wall therein, a large number of brick shapes have been required.

An object of my invention is to provide a brick, a plurality of which may be used for building these walls or linings, the single shape being all that is required for the entire wall or lining. A brick of the required shape provides for interlocking engagements with other duplicate bricks at the sides or edges and is of generally arcuate outline in end elevation. Thus, by a single pattern a plurality of the bricks may be constructed for use in building the described linings and bridge walls.

The invention will be more readily understood by referring to the accompanying drawing, in which:

Fig. 1 is a transverse sectional view thru a locomotive fire box showing the application of a bridge wall and lining in a barrel combustion chamber;

Fig. 2 is a longitudinal sectional view taken on the center line to illustrate the interlocking feature in a bridge wall and also in a circular lining;

Fig. 3 is a fragmentary enlarged elevation of the wall;

Fig. 4 is a fragmentary sectional view of the wall and lining taken on the line 4—4 of Fig. 3 illustrating more clearly the interlocking arrangement;

Figs. 5 and 6 are perspective views, showing the brick with interlocking means for bridge wall construction;

Figs. 7 and 8 are similar views, showing the interlocking arrangement for circular construction.

The outline of the inner shell 10 of a boiler was selected to illustrate the arrangement of a bridge wall and lining; the section shown in Fig. 2 being just to the rear of the flue sheet which is not shown. Figs. 3 and 4 show an enlarged elevation and section, in order to more clearly illustrate the interlocking feature of the brick when used as a bridge wall or lining. In a firebox of the type shown, the round, barrel-like forward end of the combustion chamber renders the construction of a bridge wall or lining somewhat

difficult, and to that end I have devised a brick 11, the plurality of which may be combined in order to form the wall or lining. The brick consists of a body of generally arcuate form in end elevation, the degree of curvature being so arranged that the brick will conform to various sizes of circular chambers. For bridge wall construction, the bottom face of this brick has a continuous recess 12 therein, while the top face has a continuous rib 13, so proportioned that the 10 adjacent superposed brick will interlock. Likewise one side end 14 of each brick is curved in a radius equal to about half the transverse diameter or thickness, the opposite side end having a correspondingly shaped recess 15, likewise the 15 convexly curved side has a rib or projection 16 and the concave side has a groove or recess 17, the rib or groove being of decreasing depth to a point of disappearance into the adjacent surface. In other words, the rib 16 which is a continuation 20 of the rib 13 disappears and merges into the recess 12 on the bottom face of the brick. Perhaps the construction can better be explained by saying that, in effect the two ends of the brick being held against movement, the central portion is 25 bodily displaced diagonally upward. This provides the necessary ribs and recesses for complete interlocking, without changing the cross sectional area. This describes the brick as applied to the bridge walls.

By further reference to Figs. 1 and 2, and to 30 7 and 8 which show the outline of an inner shell of a boiler with bridge wall and protective lining, it will be noted I have shown a modification of this novel arcuate brick with bosses and recesses 35 on the sides to provide means of interlocking in the longitudinal or vertical direction as the case might be. To the aforementioned brick which I have indicated at 11*, I have added a boss or projection 18 and a recess or groove 19 which form 40 complementary bosses and recesses for locking and holding a plurality of bricks in a complete ring or circle and for interlocking with an adjacent ring or circle to complete a lining of any 45 cylindrical vessel and prevent relative movement. The ribs and recesses also act as a baffle or protecting agent against the infiltration of the elements, adding further protection to the shell 10.

In the brick for lining purposes the shape is the 50 same as that used for the bridge wall and the sides are formed with complementary projections and recesses. However, instead of interlocking ribs and recesses on the faces as in the case of the bridge wall bricks they are provided on the ends. 55

Thus each brick in the lining is locked on four sides.

Thus it will be seen that a brick of generally arcuate form in shape and elevation may be combined with other bricks of duplicate shape to build up a transverse bridge wall or protective lining within a curved space, a single brick pattern being used for each construction.

While in the drawing I have shown the top 10 surface of the bridge wall as irregular, it will be understood that it may be made flat and regular if desired by breaking the top bricks to provide a level surface.

Obviously changes in form and arrangement of 15 the brick may be made, within limits, without departure from the spirit of my invention. For example, a narrower section of material constituting a mere rib and groove may be preferred, the principle of the interlock remaining the same.

20 I claim:

1. In firebox construction, the combination with a generally circular combustion chamber of a bridge wall extending across the same, said wall being composed of a plurality of duplicate oblong, flat bricks of generally arcuate form relative to a transverse horizontal axis, one side of each brick being concave and the other side convex, a portion of the body of the brick between

the ends being displaced diagonally relative to the end portions of the brick, whereby to provide a projecting portion on one face and on one side and a recess of an extent the same as the projection on the other face and on the other side.

2. A generally oblong, flat brick for firebox construction composed of an arcuate body of refractory material the curvature being relative to a transverse horizontal axis, one side of the brick being concave and the other side edge convex, a portion of the body of the brick between the ends being displaced diagonally relative to the end portions of the brick, whereby to provide a projecting portion on one face and on one side and a recess of an extent the same as the projection on the other face and on the other side.

3. A generally oblong, flat brick consisting of an arcuate body of refractory material the curvature being relative to a transverse horizontal axis, the sides of which at the ends of the brick are respectively convex and concave, and a portion of the body of the brick between the ends is located to provide a projection on one face and one side and a recess on the diametrically opposite face and side.

JAY B. TRACY.
